UNITED STATES PATENT OFFICE.

JOHN FLINK, OF PHILADELPHIA, PENNSYLVANIA, ASSIGNOR TO JOHN L. JAMIESON,
OF PHILADELPHIA, PENNSYLVANIA.

CARBON AND GAS CONSUMER.

Application filed December 30, 1921. Serial No. 525,880.

To all whom it may concern:

Be it known that I, JOHN FLINK, a citizen of the United States, residing at Philadelphia, in the county of Philadelphia and State of Pennsylvania, have invented 5 new and useful Improvements in Carbon and Gas Consumers, of which the following is a specification.

This invention relates to means for promoting combustion in furnaces, domestic heaters, boilers and the like, and it has for its primary object to provide a novel construction of device whereby the smoke and combustible gases ordinarily carried away to 15 waste are more effectively consumed than heretofore possible and incidentally the attainment of a higher degree of economy in the use of fuel.

Another object of this invention is to 20 provide a device of the character referred to which ensures increased cleanliness in the handling of a furnace or heater as well as reducing to a minimum the nuisance arising from atmospheric smoke pollution.

25 A further object of this invention is to provide a device of the kind above specified which can be readily attached to the fire door of a furnace, heater or boiler which can be so regulated relative to the bed of 30 burning fuel as to ensure the maximum efficiency in consumption of the smoke, gases and unconsumed products of combustion arising from said burning fuel.

A still further object of this invention is 35 the provision of a device of the nature referred to which is of simple construction, cheap to manufacture and install, whilst being very effective for the purpose for which it has been devised.

40 With the foregoing and other objects in view as will be more apparent from the following description, my invention consists essentially of a carbon and gas consumer attachment for the doors of heaters, boilers 45 and furnaces, characterized by the fact that a regulatable supply of combined vapor and atmospheric air is directed into the products of combustion arising from a bed of burning fuel at that point which will most effectively 50 promote their complete—or substantially complete—consumption.

In the further disclosure of the invention reference is to be had to the accompanying sheet of explanatory drawings illustrative of 55 one practical embodiment of my invention

and in which like characters of reference designate the same or corresponding parts in all the views.

Figure 1 is a sectional plan of an ordinary domestic heater having my novel carbon and gas consuming attachment applied 60 therein.

Figure 2 is a broken longitudinal sectional elevation of the carbon and gas consuming attachment drawn to an enlarged scale for 65 the sake of clearness; and,

Figure 3 is a sectional plan taken approximately on the line 3—3 in the preceding figure.

Referring more particularly to the views 70 the numeral 4 designates an ordinary domestic heater furnace having a fuel feed opening 5 closed by a hinged door 6 all of said parts being in accordance with well known construction and constituting no part 75 of this invention, reference being again made thereto later on for a better understanding of the application thereto and use of my improved carbon and gas combustion 80 promoting device.

This carbon and gas combustion promoting device comprises a substantially circular casing or mixing chamber 7 having an inner concavo-convex portion 8 and an outer concentric dished or annular chamber 9, 85 both of which are closed in by an integral flat cover or top 10. Communication between the inner concavo-convex portion 8 and outer concentric dished or annular chamber 9 is established through a small 90 horizontal orifice 11, whilst said outer chamber 9 is provided with a series of lateral and radially disposed pin holes 12 for the purpose later on explained.

Appropriately screw-threaded or otherwise connected into an enlargement or boss 13 integral with the aforesaid mixing chamber 7 is a horizontally disposed tube or pipe 14, the outer end whereof is fitted with a counterbored sleeve or 100 open ended thimble 15. Axially concentric with the tube or pipe 14 is an inner tube 16 having its inner end connecting into the aforesaid concavo-convex portion 8 of the mixing chamber 7 whilst its outer end is 105 screw-threaded or otherwise securely attached at 17 into the smaller end of the counterbored sleeve 15, and it is to be noted that by this arrangement and assembly of parts when the said counterbored sleeve 15 110

is unscrewed from connection on the tube or pipe 14 the inner tube 16 is bodily withdrawn whereby an easy means is provided for cleaning purposes and the like.

- 5 Longitudinally of the tube or pipe 14 and on the outer surface thereof I provide or attach a key-strip 18 suitably held in place by set screws 19, said key-strip 18 serving to prevent rotation of a sleeve 20 relative to 10 the tube or pipe 14. This sleeve 20 is an easy fit on the tube or pipe 14 and it is provided at one end with an integral flange 21 and at the other end it is screw-threaded at 15 22 for the reception of a clamping collar or lock-nut 23 whereby said sleeve 20 is securely connected by passage through a hole 24 provided for the purpose to the aforementioned furnace door 6. From the foregoing it will be clearly seen that by the just 20 described means the tube or pipe 14 and connected mixing chamber 7 may be moved or slid inwardly or drawn outwards relative to the inner face of the furnace door 6 whereby a simple means is provided for disposing 25 of the mixing chamber 7 at that point in the furnace 4 best suitable for the most economic consumption of the products of combustion that would otherwise be carried away to waste as unburnt heat producing matter.
- 30 Still further it will be observed that by the sliding fitment of the pipe or tube 14 in the furnace door 6 provision is made for the attachment of my novel carbon and gas consuming device to furnace, heater and boiler doors 35 of comparatively narrow dimension in that by retracting said tube or pipe 14 to its fullest extent the mixing chamber 7 can be drawn into abutment or close proximity to the inner face of the door 6 and thus 40 offer no obstruction to its free opening and closing, as well as not projecting to an objectionable extent therefrom when said door 6 is open. This latter feature I deem of considerable importance as most, if not all 45 of the prevailing devices of analogous nature in use at the present time are rigid fixtures on a furnace, heater or boiler door and protrude therefrom several inches, thereby not infrequently causing injury when firing as well as interfering with the efficient serving 50 of fresh fuel when said door cannot be swung fully open or out of the way.

Fitted into and connecting with the larger bore of the aforementioned counterbored sleeve or thimble 15 is one end 25 of a T-handle or similar cock 26, the other end 27 whereof supports and is securely attached into the bottom of a cylindric cup or vessel 28 suitably provided with a hinged or removable cover 29; and plugged into the aforesaid end 25 is a wick 30 of appropriate nature for a purpose later on explained.

Pivoted by a set screw 31 on the outer end of the aforesaid counterbored sleeve 15 60 is a pendulum gate or damper 32 having an

aperture 33 therein which may be brought into more or less registration with the open end of the inner tube 16 for regulating the amount of atmospheric air entering the device, and said gate or damper 32 may be 70 provided with a flexed portion or tongue 34 for ensuring its frictional retention at the requisite adjustment as will be well understood by those acquainted with the art to which this invention appertains. 75

In use and assuming that my novel carbon and gas consumption promoting device is—as shown—clamped to a furnace door 6 of an ordinary domestic heater 4 by means of the sleeve 20 and lock nut 23, the owner 80 or user thereof will first of all fill the cylindric cup or vessel 10 with water. Assuming also that the device has been accurately adjusted for the most beneficent results relative to the bed of burning fuel in the furnace; that is to say, the mixing chamber 7 has been positioned relative to the furnace door 6 at such distance therefrom by the inward sliding of the tube or pipe 14 so that said mixing chamber will not be affected 90 by any cold drafts or adverse currents. The gate or damper 32 is next moved pendulum fashion for the admission of atmospheric air through the inner tube 16 to the concavo-convex portion or chamber 8, and 95 at the same time, the T-handle or similar cock 26 is opened sufficiently to permit water to saturate the wick 30 and drop by drop into the space surrounding the inner tube 16 where it is rapidly vaporized and in its 100 passage through the outer tube or pipe 14 to the annular chamber 9 becomes superheated. The heated air escaping through the horizontal orifice 11 is thoroughly mixed in the annular chamber 9 with the superheated vapor. In view of the fact that the mixing chamber 7 is so located relative to the bed of burning fuel as to be constantly heated to a high temperature, and as far as practicable enveloped in the unburnt 110 products of combustion and gases arising from said burning fuel, the highly heated vapor discharging through the pin holes 12 from said mixing chamber 7 will considerably promote effective combustion by 115 commingling with the unburnt products and gases.

From the foregoing description it will be readily seen that by my invention I have provided a very simple and efficient means 120 for supplying highly heated vapor—superheated steam and atmospheric air—in a pre-determined or controllable ratio whereby the practical and substantially complete consumption of any unburnt products of combustion and gases arising from a bed of burning carbonaceous material may be accomplished.

Whilst there has been shown and described one practical embodiment of my invention 130

the same is not to be conservatively construed in that many structural changes or variations may be effected without departing from the spirit and scope of said invention, and the right is hereby reserved to make such changes and the like as fairly lie within the scope of the appended claims.

Having described my invention, what I claim as new and desire to secure by Letters 10 Patent is:

1. A carbon and gas consuming device for heaters, boilers or furnaces comprising a vapor mixing chamber for disposition in and envelopment of the unburnt products 15 of combustion, said vaporizing chamber embodying an inner concavo-convex portion and an outer communicating annular portion, means for supplying a regulated quantity of atmospheric air to the inner concavo-convex portion, means for supplying a regulated quantity of water into the device and vaporizing and superheating the same before its commingling with the heated air in the aforesaid outer annular portion, and 25 means for diffusing the vaporized mixture with the unburnt products arising from the burning fuel to promote their complete combustion.

2. A carbon and gas consuming device for 30 heaters, boilers or furnaces comprising an enclosed vapor mixing chamber for disposition in and envelopment by the unburnt products of combustion, said vaporizing chamber embodying an inner concavo-convex portion and an outer communicating annular portion, means for supplying a regulated quantity of atmospheric air to the inner concavo-convex portion, means for supplying a regulated quantity of water into the device and vaporizing and superheating the same before its commingling with the heated air in the aforesaid outer annular portion, and means for diffusing the vaporized mixture with the unburnt products arising 45 from the burning fuel to promote their complete combustion.

3. A carbon and gas consuming device for 50 heaters, boilers or furnaces comprising an enclosed vapor mixing chamber for disposition in and envelopment by the unburnt products of combustion, said vaporizing chamber embodying an inner concavo-convex portion and an outer concentric communicating annular portion, means for supplying a regulated quantity of atmospheric air to the inner concavo-convex portion, means for supplying a regulated quantity of water into the device and vaporizing and superheating the same before its commingling with the heated air in the aforesaid outer annular portion, and means for diffusing the vaporized mixture with the unburnt products arising from the burning fuel to promote their complete combustion.

60 4. A carbon and gas consuming device for

heaters, boilers or furnaces comprising an enclosed vapor mixing chamber for disposition in and envelopment by the unburnt products of combustion, said vaporizing chamber embodying an inner concavo-convex portion and an outer concentric communicating annular portion, means for supplying a regulated quantity of water into the device and vaporizing and superheating the same before its commingling with the 70 heated air in the aforesaid outer annular portion, means for diffusing the vaporized mixture with the unburnt products arising from the burning fuel to promote their complete combustion, and means for slidably 75 supporting the device in the heater, boiler or furnace door whereby the mixing chamber may be moved toward or away therefrom.

5. A carbon and gas consuming device for 80 heaters, boilers or furnaces comprising an enclosed vapor mixing chamber for disposition in and envelopment by the unburnt products of combustion, said vaporizing chamber embodying an inner concavo-convex portion 90 and an outer concentric annular portion, a pipe having one end secured into and connecting with the outer concentric annular portion of the mixing chamber, a counterbored sleeve removably mounted on the outer end of said pipe, an inner tube secured to the counterbored sleeve and axially concentric within the aforesaid pipe, the inner end of said tube having removable connection into the concavo-convex portion of the vapor 95 mixing chamber, means for regulating the supply of atmospheric air into the inner tube, means for supplying a regulated quantity of water into the aforesaid pipe, means for distributing the superheated mixture 100 from the vaporizing chamber into the unburnt products arising from the burning fuel to promote their complete combustion, and means for slidably supporting the device in the heater, boiler or furnace door 105 whereby the mixing chamber may be moved 110 towards or away therefrom.

6. A carbon and gas consuming device for 115 heaters, boilers or furnaces comprising an enclosed vapor mixing chamber for disposition in and envelopment by the unburnt products of combustion, said vaporizing chamber embodying an inner concavo-convex portion and an outer concentric communicating annular portion, a pipe having 120 one end secured into and connecting with the outer concentric annular portion of the mixing chamber, a counterbored sleeve removably mounted on the outer end of said pipe, an inner tube secured to the counterbored sleeve and axially concentric within the aforesaid pipe, the inner end of said tube having removable connection into the concavo-convex portion of the vapor mixing 125 chamber, an apertured damper for regulat- 130

ing the supply of atmospheric air into the inner tube, means for supplying a regulated quantity of water into the aforesaid pipe, means for distributing the superheated mixture from the vaporizing chamber into the unburnt products arising from the burning fuel, to promote their complete combustion, and means for slidingly supporting the device in the heater, boiler or furnace door 10 whereby the mixing chamber may be moved relative thereto.

7. A carbon and gas consuming device for heaters, boilers or furnaces comprising an enclosed vapor mixing chamber for disposition in and envelopment by the unburnt products of combustion, said vaporizing chamber embodying an inner concavo-convex portion and an outer concentric communicating annular portion, a pipe having 15 one end secured into and connecting with the outer concentric annular portion of the mixing chamber, a counterbored sleeve removably mounted on the outer end of said pipe, an inner tube secured to the counterbored sleeve and axially concentric within the aforesaid pipe, the inner end of said tube being removably connected into the concavo-convex portion aforesaid, an apertured damper for regulating the supply of 20 atmospheric air into the inner tube, a vessel for a supply of water having a valved control for feeding said water drop by drop into the aforesaid pipe wherein it is vaporized, and means for distributing the superheated mixture from the vaporizing chamber into the unburnt products arising from the burning fuel to promote their complete combustion, and means for slidingly supporting the device in the heater, boiler or 25 furnace door whereby the mixing chamber may be moved relative thereto.

8. A carbon and gas consuming device for heaters, boilers or furnaces comprising an enclosed vapor mixing chamber for disposition in and envelopment by the unburnt products of combustion, said vaporizing chamber embodying an inner concavo-convex portion and an outer concentric communicating annular portion, a pipe having 30 one end secured into and connecting with the outer concentric annular portion of the mixing chamber, a counterbored sleeve removably mounted on the outer end of said pipe,

an inner tube secured to the counterbored sleeve and axially concentric within the aforesaid pipe, the inner end of said tube being removably connected into the concavo-convex portion aforesaid, an apertured damper for regulating the supply of atmospheric air entering the inner tube, a vessel 55 for a supply of water having a valved control for feeding the same drop by drop into the aforesaid pipe wherein it is vaporized, radial holes horizontally arranged in the outer wall of the aforesaid annular chamber 60 for distributing the superheated mixture into the unburnt products arising from the burning fuel to promote their complete combustion, and means for slidingly supporting the device in the heater, boiler or furnace 65 door whereby the mixing chamber may be moved relative thereto.

9. A carbon and gas consuming device for heaters, boilers or furnaces comprising an enclosed vapor mixing chamber for disposition in and envelopment by the unburnt products of combustion, said vaporizing chamber embodying an inner concavo-convex portion and an outer concentric interconnected annular portion, a pipe having 70 one end secured into the outer concentric annular portion of the mixing chamber, a counterbored sleeve removably mounted on the outer end of said pipe, an inner tube secured to the counterbored sleeve and axially concentric within the aforesaid pipe, the inner end of said tube being removably connected into the concavo-convex portion 75 aforesaid, an apertured damper for regulating the supply of atmospheric air entering 80 the inner tube, a vessel for a supply of water having a valved control for feeding the same drop by drop into the aforesaid pipe wherein it is vaporized, radial holes horizontally 85 arranged in the outer wall of the aforesaid annular chamber for distributing the superheated mixture into the unburnt products arising from the burning fuel to promote their complete combustion, and a sleeve slid- 90 ingly feathered on the aforesaid outer pipe 95 whereby the device can be supported in a furnace, heater or boiler door, and means for clamping said sleeve rigidly thereto.

In testimony whereof I affix my signature.

JOHN FLINK.
